UNITED STATES PATENT OFFICE

CHARLES TRAVIS, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

GLOW DISCHARGE DEVICE

Application filed January 17, 1928. Serial No. 247,293.

My invention relates to asymmetrical conductors of the gaseous discharge type utilizing for any suitable purpose and particularly for procuring from an alternating current a substantially uni-directional current suitable to be employed for any suitable purpose including that of energizing the electrode and particularly the anode or plate circuits of thermionic tubes.

10 In accordance with my invention, electrodes of a rectifier tube of the point-plane type are comprised of elements of such form and disposition that the rectified voltage supplied by the tube and its power output per unit of active anode surface attain orders of magnitude not hitherto realized, more particularly the cathode structure comprises two foraminous tubular members disposed one within the other about an anode and more specifically, either and preferably both cathode members are formed by a helix of wire of small cross-sectional diameter or radius of curvature.

15 Also in accordance with my invention, within a tube of the character above described, there are disposed members, as for example, electrodes, or parts of electrodes, and specifically cathodes, of metals, preferably molybdenum and tantalum, having different gas-occludent properties continually to maintain gas within the tube in a state of high purity. More specifically, the cathode is comprised of a molybdenum member heated in hydrogen substantially at atmospheric pressure, and to which is subsequently affixed a member, as a loop or ring, of tantalum; preferably, the cathode after assembly is disposed within the envelope of the tube and heated in a high vacuum.

20

25 My invention further resides in features of structure, arrangement and combination hereinafter described and claimed.

For an illustration of some of the various forms my invention may take reference is to be had to the accompanying drawings, in which:

30

Fig. 1 is a vertical elevational view, partly in section, of a gaseous discharge tube embodying my invention.

Fig. 1a is a horizontal sectional view, parts in plan, taken on the line 1a—1a of Fig. 1.

Fig. 2 is a vertical elevational view, partly in section, of a modified structure.

Fig. 2a is a horizontal sectional view, parts in plan, taken on the line 2a—2a of Fig. 2.

Fig. 2b is a horizontal sectional view, parts in plan, of a modified cathode-structure support.

Fig. 3 to 8 inclusive are fragmentary elevational views, partly in section, of modified electrode structures.

Figs. 3a to 8a are plan views of the structures shown in Figs. 3 to 8 respectively.

Fig. 9 is a diagram of one of the various electric circuit arrangements in which a form of my gaseous discharge tube is utilizable.

Referring to Figs. 1 and 1a, 1 is the base of a tube or bulb B of glass or the like having the usual tubular stem 2 and press 3, of glass or equivalent.

Secured to or sealed in the press 3 are upstanding supports, wires or rods 4, at least one of which is connected as by a conductor 5 to a contact tip 6 disposed exteriorly of the bulb B and preferably, as shown, secured to the bottom face of the base 1 to engage a contact member of a suitable receptacle or socket, not shown. The cathode member C comprises numerous elements of fine wire 7 of molybdenum, tantalum, tungsten, nickel or other suitable material, but preferably molybdenum, ranging in diameter from about .006 to .015 inch, effecting small radius of curvature of its surface for effecting high electron emission.

The wire 7 is disposed, in the example illustrated, in the form of a helix, all or any suitable number of convolutions of which are secured, as by welding, to supports 8 which are secured at one end, preferably the lower end, to main support members 4, and at the other end, preferably to a cross support or brace member 9 secured, as by welding, to the upper, or free ends of the main support rods 4.

The wires or main support rods 4 are preferably of a diameter greater than that of supports 8 and may be, for example, of the order of .04 inch, the diameter of the wires 8 being

of the order of .025 inch. Preferably, and as shown, the main support or sustaining wires or rods 4, at their lower ends have a portion extending at a substantial angle intermediate the vertically upstanding portion of the rod and the point at which it is sealed in the press 3 to permit longitudinal expansion of the support and thus prevent appreciable distortion or displacement of the cathode elements 7 which would otherwise occur due to the high and varying temperatures to which the structures are subjected during construction and operation of the tube. Similarly and for like purpose the supports 8 to which the cathode member is directly secured is bent at its lower end for attachment, as by welding, to the main support rods 4 and at its upper end is secured to the support 9 at a point spaced from that at which the latter is secured to the main support 4.

Also secured to the press 3 are the upstanding rods or wires 10, at least one of which is connected as by a conductor 11 to a contact tip 12 suitably secured in the base 1 and extending exteriorly thereof for engagement by contact structure of a suitable socket, not shown. The electrode or cathode member C1 comprises numerous elements of fine wire 13 of tantalum, tungsten, molybdenum, nickel or other suitable material, but preferably molybdenum, ranging in diameter from about .003 to .010 inch, effecting small radius of curvature of its surface for effecting high electron emission.

To facilitate manufacture, the portion of the support 10 to which the elements are fastened, as by welding, is welded or otherwise intimately secured to the lower portion sealed in press 3.

The wire 13 is disposed, in the example illustrated, in the form of a helix, all or any suitable number of convolutions of which are secured, as by welding, to the supports 10, the support being essential or at least practically desirable because of the fineness of wire 13.

Preferably, and as shown, the diameter of wire 13 is less than that of wire 7 and the turns of helical cathode member C1 are more closely spaced than those comprising the electrode member C.

Adjacent the press or seal 3 the anode 14 is surrounded by a tube 15 of refractory insulating material, as lava, lavite, soapstone, or equivalent, emerging from the press 3 and having a coefficient of thermal expansion substantially equal to or differing but slightly from that of the material of the press 3. Within the tube 15 and exteriorly of the press 3 the anode 14 is welded at W to a conductor 16 extending to and in electrical engagement with a contact tip 17 which may be secured to the base 1. The lead-in conductor or wire 16 is of ordinarily such diameter and ductility that it would not suitably

support anode 14. As shown, the bore of the refractory tube 15 is sufficiently small to permit the anode to be supported at least in part and maintained in proper position by the tube. By securing and supporting the anode in the manner described, there is little or no danger of cracking the press 3 by expansion and contraction of the anode 14.

The anode may be of tantalum wire having a diameter of from about .015 to .03 inch, but preferably .02 inch. It may project roughly about $\frac{5}{8}$ inch above the top of the refractory sleeve 15, in which case the inner cathode member C1 may be roughly 1 inch long and disposed to extend above and below the exposed portion of the cathode, and the outer cathode member C may be roughly $\frac{7}{8}$ inch long. It is to be understood that the length of either or both electrode cathode members C and C1 can be increased, although but little additional output is gained thereby. The length may be decreased with, however, appreciable decrease in efficiency of the tube. For the dimensions given, the diameter of the inner cathode member may be approximately .2 inch and that of the outer cathode member about .3 inch. It is understood that the dimensions given above and throughout the specification are used in an illustrative and not a restricted sense, and that when suitable or desirable may be modified.

The support wires 4, 8, 9 and 10 may be of suitable material, such as that of wire 6, but preferably of nickel. When the cathode members are of molybdenum, as above described, it is in some instances desirable that one of the support members be of tantalum, since the presence of these two metals having different occludent properties by selective clean-up action continually maintains a state of high purity of the gas within the bulb B, which is or may be a pure monatomic gas or vapor as neon, argon, but preferably helium at an absolute pressure from about 5 to 50 mm. of mercury, preferably about 24 mm. of mercury. It is more convenient, however, to make the tantalum member in the form of a ring such as the loop or ring 18 disposed at one end, preferably the upper end of a cathode member, as, for example, the outer cathode C of Fig. 1, and secured to the supports thereof, as rods 8, in any suitable manner, as by welding, after de-gassing of the molybdenum cathode by heating in hydrogen, which may be substantially at atmospheric pressure. The assembled cathode with the tantalum attached thereto is disposed within the tube envelope B and heated, as by induction, in a substantially high vacuum.

There may be provided a stem member 19, as of glass, projecting upwardly from the press 3 whose exterior diameter is sufficient-

ly great to position and support the inner electrode member C1.

The anode 14 and the outer cathode member C may be connected, respectively, to the positive and negative conductors of a direct current source subject to voltage fluctuations and a resistance of desirable magnitude connected between the anode 14 and the interposed electrode member C1 to maintain substantially constant within unusually narrow limits the voltage between the conductors notwithstanding variations of load and fluctuation of the source of supply. A system utilizing a gaseous discharge tube constructed in accordance with my invention and having a resistance whose disposition as above identified is disclosed and described in co-pending application Serial No. 225,469, filed October 11, 1927.

By effecting direct electrical contact between contact tips 12 and 17, as by use of a common socket contact spring, not shown, and by connecting the discharge tube in the usual manner, i. e., in series in a circuit including a source of alternating or fluctuating current and devices adapted to be operated by direct current, the device operates as a half-wave rectifier whereby unidirectional current impulses flow in the circuit. Due to the construction of the cathode, as above described, the efficiency of the rectifier is increased without decrease of life and in addition the potential, at which there occurs ionization of gas within the tube necessary to effect starting thereof, is lowered. Furthermore, and contributing to the increase of efficiency, the drop of potential within the tube is substantially decreased.

Fig. 2 of the drawing illustrates a full wave rectifier having features of construction in common with the gaseous discharge tube of Fig. 1. In this modification the lower ends of the support wires 8' holding the outer cathode member C are secured as by welding to inwardly extending supports 8'', preferably of reduced cross section, and welded to the vertical portion of the main support rods 4. The supporting rods or wires 10' for the inner cathode member C1 are secured as by welding to the top cross support or brace member 9 at points substantially distant from those at which the brace member is welded to the main supports 4. The lower ends of the inner cathode member supports 10' are bent outwardly at a substantial angle and welded at or near their ends to main support rods or wires 4. As in Fig. 1 the supporting frame work for the cathode members is constructed to permit relative longitudinal expansion of the separate elements comprising the frame work without appreciable distortion or displacement of the cathode elements carried thereby. To permit of full wave rectification there is provided a second anode member 14' constructed, supported,

and arranged substantially as above described with respect to anode 14 of Fig. 1. The upwardly extending glass stem members 19 and 19' disposed, respectively, about the refractory lavite tubes 15 and 15' may be of such diameter and so disposed as to position and support the inner electrode member C1 which may be, as is most clearly shown in Figs. 2 and 2a, a single conductor wound in the form of a helix and whose individual convolutions, when viewed in plan, are in the form of two substantially completed circles joined at adjacent discontinuities of their respective peripheries. The outer, cathode member C may also be a single conductor wound in the form of a helix whose individual convolutions, as shown in Fig. 2a, are, in effect, two semi-circles, the opposite and adjacent ends of which are joined by parallel and integral members the centers of curvature of the curved portions of both cathode members C and C1 is preferably at the anodes 14 and 14' whereby the cathode members or a substantial portion of them are symmetrically disposed about the anode structures to effect more even distribution of the glow discharge.

In Fig. 2b, the tubes 15 and 15', of lava, lavite, or the like, are each provided with a stiffening shoulder engaging the press 3 and a portion of enlarged diameter to position and support inner electrode C1. This construction is particularly of advantage when caesium is utilized as an ionizing agent, as the presence of heated glass, especially lead glass, as stems 19 and 19', reduces or destroys its efficacy.

The cathode structure of Figs. 3 and 3a is that of a half-wave rectifier and is generally similar in construction to the disclosure of Fig. 1. However, the supports 10' of the inner cathode member, instead of being electrically and mechanically independent of the outer cathode structure, within the tube, are secured at their upper ends to the cross support rod 9 and at their lower ends bent outwardly to the main support rods or wires 4, as in the modification of Fig. 2. With such construction the support wires 10' for the inner cathode may be of the same or approximately the same diameter as that of the rods 8 which support the outer cathode member C.

Referring to Fig. 4, the outer cathode C is comprised of two separate helixes whose individual convolutions are circular and symmetrically disposed with respect to the anodes 14 and 14'. The support rods 8 are secured as by welding to all or suitable number of the convolutions of each helix at opposite sides of the helixes and preferably in their line of centers. The upper ends of the supports are suitably secured to the cross strip 9 and at their lower ends to the main support rods 4. The auxiliary support rods 20, 20 for the cathode assembly C are secured to

the respective helixes at or near their point of closest approach and to each other at adjacent ends as disclosed. The inner cathode structure C1 consists of two helixes disposed about the anodes and within the corresponding helix of the outer cathode member C. Each inner helix is supported by a rod or wire 21 suitably secured thereto and whose upper and lower ends are welded to the cross support 9 and the outer cathode support 8, respectively. The inner cathode helixes are further braced and supported by the depending rods or wires 22 welded at their upper ends to the cross support 9 and intermediate their length to the convolutions of the respective helixes. The glass stem members 19 and 19' projecting upwardly from the press 3 engage the lower ends of the support wires 21 and extensions of depending rods 22 to position the inner cathode helixes.

In Figs. 5 and 5a there is disclosed a further modification of cathode structure in which the individual convolutions of the outer cathode member C comprise in effect three circles having their centers in the same straight line, the outer two of which are of relatively large diameter and symmetrically disposed with respect to the anodes 14 and 14' and the inner one of which is formed by bending the wire comprising the turn about the central main support rod 4a which is sealed at its lower end within the press 3 and at its upper end suitably secured to the cross support rod 9. The inner cathode member, as in Fig. 4, consists of two separate coils or helixes. The depending members 23 of rod or wire are secured at their upper ends to the cross brace 9, their lower free end engaging the inner peripheries of the glass stems 19, 19' to properly position the helixes as above explained.

The construction shown in Figs. 6 and 6a is generally similar to that disclosed in Figs. 5 and 5a except that the auxiliary main support 4a and the inner cathode structure is omitted.

In the construction shown in Figs. 7 and 7a the inner cathode member C1 is generally similar to the construction of the outer cathode member C of Fig. 4. In this modification the outer cathode structure C is similar to that of the inner cathode member C of Fig. 2a.

As indicated in Figs. 8 and 8a the cathode members C and C1 may each comprise a tubular member of screening, the mesh of the inner cathode member preferably being finer than that of the outer cathode member.

It is to be understood that the number, size and shape of the cathode elements or their equivalent may be varied without departing from the spirit of my invention. Further, while cathode elements are shown and described as wire of substantially circular cross section, it shall be understood that any other

suitable cross section is comprehended by the term "wire", and may be polygonal, including such cross sections as are afforded by strips or ribbons whose edges or flat sides may be presented to the co-acting anode.

What I claim is:

1. A gaseous discharge device comprising anode structure, cathode structure comprising a wire-like helix of molybdenum and a closed loop of tantalum.

2. A gaseous discharge device comprising anode structure, cathode structure comprising a wire-like helix whose surfaces have radii of curvature lying within the range of from about .003 to .0075 inch, and an electrode positioned between said anode and cathode structures and comprising a wire-like helix whose surfaces have radii of curvature lying within the range of from about .0015 to .005 inch.

CHARLES TRAVIS.
